UNITED STATES PATENT OFFICE.

RICHARD SMITH, OF SHERBROOK, CANADA.

SCREEN FOR PAPER-MAKING MACHINES.

SPECIFICATION forming part of Letters Patent No. 628,234, dated July 4, 1899.

Application filed June 30, 1898. Serial No. 684,903. (No model.)

To all whom it may concern:

Be it known that I, RICHARD SMITH, residing at Sherbrook, in the county of Sherbrook, Province of Quebec, Canada, have invented 5 certain new and useful Improvements in Screening Mechanism for Paper-Making Machines, of which the following is a specification.

This invention relates to screening-ma- 10 chines having a diaphragm arranged below the screen and provided with means for vibrating said diaphragm, so as to produce an alternate suction and blast through the slits:

The said invention consists, chiefly, in cer- 15 tain improvements in the construction and combination of the said strainer-plates and their frame whereby said plates may easily be inserted horizontally in position and withdrawn therefrom, they being held securely in 20 said frame without any risk of accidental displacement or injury.

The said invention also consists in certain improvements in the spring which acts on the diaphragm whereby it is double instead of 25 single and will continue to be operative in case either spring happens to break.

The drawings accompanying this specification represent, in Figure 1, a part side elevation part vertical section of my improved 30 screen; in Fig. 2, a plan, and in Fig. 3 a vertical section, of one end of such screen. Fig. 4 is a plan, Fig. 5 an end view, and Fig. 6 an edge view, of the screen-plate. Fig. 7 is a face view, and Fig. 8 a vertical section, of the 35 locking device, to be hereinafter explained. Fig. 9 represents a detail sectional view of a modification of the device shown in Fig. 3.

In the drawings, 11 represent the end housings of the general structure of a screen for 40 screening pulp in a paper-machine, such housings being connected by cross-beams after the usual manner of such structures.

The rectangular frame of the screen is shown at 2, its front and rear bars being 45 shown, respectively, at 3 3' and its sides at 44'.

The screen-plates are several in number, as shown at 5, &c., and the slots of the same at 6 6 6, &c. The side edges 5' 5' of each screen-plate are beveled, and these beveled edges 50 are adapted to enter correspondingly-formed grooves 8 in opposite sides of the screen-frame, the dovetailed joint thus produced ef-

fectually securing the plate in place against any loosening in a vertical direction and preventing any fracture of such plate, which 55 would otherwise occur at the points of the screw-heads. The inner or rear edge of the screen-plate may also be beveled to engage a groove in the rear bar of the screen-frame.

The side edges of the screen are slightly 60 wedge-shaped in the direction of their length, as shown at 8' in Fig. 6 of the drawings, and the grooves 8 in the screen-frame are of corresponding shape. An equivalent of the beveled joint between the screen frame and plate 65 would be a shelf-groove and tongue, as shown in Fig. 9 of the drawings, which represents a section of the parts. When the plate is driven home, the wedge-joint thus formed prevents under all ordinary circumstances any longitudinal loosening of the plate; but to provide 70 extreme protection against such loosening I employ a locking device, which in the present instance is composed as follows:

9 represents a latch-plate of a length ap- 75 proximating the width of the screen-plate, this latch-plate being hinged at its lower edge to the front side bar of the screen-frame and below the opening in the latter, through which the screen-plate is inserted, the said 80 hinge being shown at 10. To lock the latch-plate in its closed position, I employ two horizontal lugs 13 13, formed upon or secured to the bar 3 of the screen-frame and having each a vertical slot 14 to receive a wedge 15. The 85 upper part of the latch-plate has slots 16 16 to embrace or inclose the lugs 13. When in a closed or locked state, the latch-plate is prevented from dropping by the wedges. To release said latch-plate, the wedges are removed 90 and the plate lowered, thus exposing the screen-plate and permitting of removal of the latter.

The cam of the mechanism for vibrating the diaphragm is shown at 18 and the bar de- 95 pending from the bottom of a disk or plate 24, attached to the under side of the flexible dia- phragm 23, arranged under the screen-frame and operating with such cam, at 19, these features being of the construction now in 100 general use. The wooden spring proper for maintaining the lower end of the bar 19 in close contact with the cam 18 is shown at 20 as confined at its outer end to one of the

5 housings 1 in the usual manner. Such springs are cheap and preferred for other reasons in this class of machines; but as they are easily broken it becomes desirable to add another 10 spring, which will act instead of the wooden one when it breaks and increase resiliency when both act together.

15 The auxiliary or secondary spring, which constitutes one of the features of my present invention, is shown at 21 as disposed below the first, and, like the latter, is confined at its outer end to the housing 1, this secondary spring being connected with the spring proper by bolts, as shown in the drawings, or 20 in any suitable manner which permits the two to act in unison and exert a common stress upon the bar 19.

What I claim is as follows:

25 1. In combination with a screen-frame having internal, transverse grooves and openings at the ends thereof to permit the endwise withdrawal of the screen-plates, a series of screen-plates and means for holding them in the said grooves, any one of the said plates being removable horizontally and longitudinally through the sides of said frame without displacing any of the others substantially as set forth.

30 2. In combination with a screen-frame, a series of horizontally-removable screen-plates or strainer-plates, each plate being beveled

35 laterally and wedge form longitudinally, and the said frame having grooves of corresponding shape to receive the said edges, substantially as set forth.

3. A screen-frame having an opening and a screen-plate received in said opening and removable through the same, in combination with a latch-plate hinged to the said frame and a locking device for the said plate, the end of 40 the frame being grooved in the inner side to receive the end of the said plate substantially as set forth.

4. In combination with a screen-frame and a diaphragm arranged below the same, the 45 jolting mechanism acting on the said diaphragm and a compound spring acting on the said mechanism, consisting of the wooden spring ordinarily used for such purposes and a metallic spring connected thereto and co- 50 operating therewith, such additional spring being adapted and arranged to continue the resilient action on and with the said mechanism after the said wooden spring has been broken, substantially as set forth.

55 In testimony whereof I affix my signature in presence of two witnesses.

RICHARD SMITH.
